UNITED STATES PATENT OFFICE

2,542,525

MANUALLY MANEUVERABLE WEED BURNER

Ole L. Hogenson, Winger, Minn.

Application November 29, 1949, Serial No. 129,886

2 Claims. (Cl. 126—271.2)

1

This invention relates to certain new and useful improvements in portable manually maneuverable burners for weeds and underbrush and has reference in particular to those types which have a suitable handle and a freely turnable drum or cylinder which, properly ignited and flaming like a torch, is generally rolled over the surface or, where small enough, is carried in one's hand and brought into contact with the weeds in a manner to set the weeds and underbrush on fire.

As is evident from the foregoing introductory statement of the invention, weed burners which are either hand-carried like a torch or steered and rolled by a walking attendant are many and varied in types and constructions. They differ from one another in one way or another, structurally construed, and are used with varying degrees of satisfaction and success.

In some types, a ground roller or cylinder is used and, in others a fuel tank is strapped on the attendant's back and the burner or torch is manipulated by hand. In the belief that these prior art constructions are objectionable for one reason or another, it is the object of the present invention to provide a structure which, it is felt, better fulfills the requirements of manufacturers and users.

Briefly summarized, a preferred embodiment of the invention has to do with a simple, practical and economical manually maneuverable device which is characterized by a hollow handle through which volatile fuel is adapted to be supplied, preferably under pressure, a spray nozzle mounted on the discharge end of the handle for emitting the fuel in mist-like jets, a lightweight but sturdy frame structure supported from the nozzle-equipped end of the handle, and a freely rollable drum in line with the nozzle and mounted for rotation in the frame.

Novelty is predicated on the one hand, on the combination of parts depicted in Fig. 1 of the drawings and, on the other hand, on the frame, screen roller and clamp, the attachment, shown in Figs. 2 and 3.

More specifically, novelty has to do with frame means which is detachably applicable to the nozzle-equipped end of spray-type fuel pipe, there being a screen roller mounted in said frame means and said roller being hollow so that when the wires get hot they vaporize the fuel and provide a ground contacting rotating torch.

Other objects and advantages will become more readily apparent from the following description and the accompanying illustrative drawings.

2

In the accompanying sheet of drawings wherein like numerals are employed to designate like parts throughout the views:

Fig. 1 is a side elevational view of a manually maneuverable burner constructed in accordance with the principles of the present invention;

Fig. 2 is a top plan view on an enlarged scale depicting with particularity the frame and roller, constituting the attachment, and the clamp for securing the attachment in place;

Fig. 3 is a view taken on the plane of line 3—3 of Fig. 2 looking in the direction of the arrows; and,

Fig. 4 is a cross section on the line 4—4 of Fig. 2, looking in the direction of the arrows.

Referring now to the drawings and particularly to Fig. 1 the reach pipe, which is the handle proper, is denoted by the numeral 6 and is provided at the upward end with a suitable hand grip 8. The hand grip has a mount 10 thereon to accommodate a fitting 12 to which the fuel supply line 14 is connected. The laterally curved end of the fuel line, the portion 16, is in communication with the fuel passage in the handle. As shown in Fig. 2 the discharge end of the handle is provided with a spray nozzle or head 18 from which the fuel, under pressure, is emitted in misty streams or jets as shown.

The frame unit is denoted by the numeral 20 and includes a pair of spaced parallel side members 22 and 24 of duplicate construction. The forward ends of said members are provided with bearings to accommodate end-journals 26 on opposite ends of a hollow screen wire drum or cylinder 28. This is sometimes referred to as a rotary torch or, alternatively, as a flaming ground contacting roller. It will be noted that the rearward end of the frame members are curved and bent laterally toward each other as at 30 and 32 and then bent again into straight parallelism as at 34 and 36 where they are disposed in spaced relation to the nozzle-equipped end of the handle. End portions 34 and 36 are secured to the handle by a two-part or sectional clamp 38. The sections have semi-circular bends 40 which embrace the pipe and have outstanding flat portions 42 and 44 secured together by bolts or equivalent fastenings 46. The free ends are formed into coating jaws or jaw portions 48 and 50 which are releasably engaged with the ends or adapters 34 and 36. The clamp may be slid along the handle to position the screened roller closer to or farther from the nozzle.

It will be obvious that the volatile jets of misty fuel shot through the orifices in the nozzle 18

will be projected to "stream" against the wires of the hollow roller or drum 28. By igniting the fuel, an intense flame will be built up around the roller and applied by the latter to destroy weeds, underbrush and debris, in an obvious manner.

It will be evident from the specification and complementary drawings that the invention, as a general rule, will take the form of a freely rollable ground contacting drum or screen which, for the most part, comes into travelling contact with the surface of the ground as the attendant pushes and pulls same by way of the handle means. I desire to have it understood, however, that both the screen drum and frame structure may be made much smaller and lighter in weight so that a simple attachment will thus be had which could be readily applied to various types of weed burners of the "flame thrower" types. That is to say, there are certain types which have to do with a tank which is strapped or otherwise mounted on the back of the attendant and which has rigid nozzle means attached to the tank by way of a flexible hose. The attachment herein shown and described would be attached to the rigid pipe which carries the spray nozzle, obviously. Therefore it is desired that the attachment be visualized as either a ground roller type or, if preferred, as a smaller type which can be conveniently carried in one's hand.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. An attachment for the nozzle equipped end of a fuel delivering handle comprising a frame embodying spaced parallel frame members, a sectional clamp adapted to be detachably and adjustably mounted on the nozzle equipped end of said handle, said frame members being detachably and adjustably joined at their rearward ends with said clamp, the forward ends of said members having bearings, and a hollow screen wire drum parallel to said clamp and located between the forward ends of said members and having end-journals mounted for rotation in said bearings, said drum being adapted to occupy a position in the path of fuel which is sprayed from said nozzle.

2. A portable weed burner adapted to be maneuvered by a walking attendant comprising a hollow handle through which a volatile fuel is adapted to flow, a spray nozzle mounted on the discharge end of said handle, a clamp mounted on said handle adjacent to said nozzle, a pair of spaced parallel frame members connected at corresponding rearward ends to said clamp, and a hollow screen wire cylinder mounted for free rotation between the forward ends of said members and spaced from and lined up with said nozzle to receive fuel which is sprayed from the latter.

OLE L. HOGENSON.
